L. COATALEN

BRAKE FOR VEHICLES

Filed Dec. 13, 1923

INVENTOR:

Louis COATALEN

by Spear, Middlem, Donaldson Hall
Atts.

UNITED STATES PATENT OFFICE.

LOUIS COATALEN, OF WOLVERHAMPTON, ENGLAND, ASSIGNOR TO SUNBEAM MOTOR CAR COMPANY, LIMITED, OF WOLVERHAMPTON, ENGLAND, A BRITISH COMPANY.

BRAKE FOR VEHICLES.

Application filed December 13, 1923. Serial No. 680,404.

REISSUED

To all whom it may concern:

Be it known that I, LOUIS COATALEN, a subject of the King of England, residing at Wolverhampton, in the county of Stafford, England, have invented certain new and useful Improvements in Brakes for Vehicles, of which the following is a specification.

This invention relates to servo-operated brakes for use on vehicles, of the kind in which two brake mechanisms are contained in a single drum, one being positively applied to the drum and being connected to the second so that movement of the first 10 operates, servo fashion, to apply the second mechanism. Hitherto for this purpose a construction has been suggested in which the drum was engaged by two expanding bands of which the first, or servo band, was a narrow one in the centre of the drum, and the end of this was connected to the end of a wide channel shaped main band the other end of which was pivoted to a fixed point.

25 The object of the present invention is to provide a construction of servo brake mechanism of this kind enabling only two shoes or blocks to be used, one operating, servo fashion, to apply the second shoe or block.

30 The figure is a side elevation showing one embodiment of the invention.

According to this invention, the drum contains two segmental shoes, one on each side of the axis of the drum and located in 35 the same radial plane, of which the first or main shoe is pivoted to a fixed point, and the second or servo shoe is free to move around the axis of the drum and is connected with the free end of the first shoe, 40 with means acting upon the servo shoe to apply it to the drum.

45 Preferably the operative connection between the servo shoe and the main shoe is such that the latter can also readily be applied directly by control mechanism which is independent of that employed for applying the servo shoe. Thus it is possible to use the main brake in the ordinary manner to hold against motion in either direction, 50 and it can also be used as an emergency brake in the ordinary manner.

In one method of carrying out the invention for an expanding brake, the shoe A forming the main brake is suspended or

supported, as by pivoting in the usual manner from one end A², and at the other end is acted upon by a cam B which is pivoted to a fixed part, such as the anchor plate C, and is provided with a short arm D or lever to effect its angular movements.

The servo brake is a single shoe E arranged inside the drum F opposite to the main brake shoe A and is at one end supported by a radius rod G, which is angularly movable about the axis F² of the brake drum, thus allowing circumferential freedom of movement for the servo brake shoe. The end of the servo brake shoe thus supported, is, by the agency of a link H, operatively connected to the arm D of the 70 cam acting upon the main brake, the disposition of the parts being such that when the servo brake shoe E is applied to the drum F its circumferential movement due to the movement of the drum acts to apply 75 the main brake A through the parts H and D.

The servo brake shoe E is acted upon by a cam J at the end remote from its suspension means so as to bring it into engagement 80 with the brake drum, and this cam as usual may be actuated from the usual brake pedal. The two shoes may be connected to one another as usual by pull-off springs K so that their arrangement in this respect 85 broadly resembles that of an ordinary expanding brake.

An important feature of the invention is the provision of means for operating the main brake shoe A quite independently of 90 the servo brake. To effect this in a simple manner the cam B which acts directly upon the shoe A is operatively connected to the side or hand brake lever as by the arm L and rod M through some form of joint 95 which may embody a flexible or sliding connection adapted to permit of the movement of the cam under the operation of the servo brake quite independently of the additional mechanism provided to operate it independently of the servo brake.

Obviously the link H is not necessary as the end of the shoe E may engage the arm D.

It will be seen from the foregoing that 105 the servo and the main brake are effectively combined together in a simple and direct manner, involving a minimum of space oc-

cupied, and virtually no parts other than would be required for an ordinary expanding or contracting brake.

What I claim as my invention and desire 5 to secure by Letters Patent of the United States is:—

1. In a brake for a vehicle, the combination of a drum, a main segmental shoe inside said drum, a servo segmental shoe also 10 inside said drum and on the opposite side of the axis of said drum, a fixed pivot for one end of said main shoe, an operative connection between the other end of said main shoe and the adjacent end of said servo 15 shoe, including a lever and a cam operated thereby, said cam engaging said main shoe.

2. In a brake for a vehicle, the combination of a drum, a main segmental shoe inside said drum, a servo segmental shoe inside 20 said drum and on the opposite side of the axis thereof from said main shoe, a fixed pivot for one end of said main shoe, an operative connection between the other end of said main shoe and the adjacent end of said servo 25 shoe, including a lever and a cam operated thereby, said cam engaging said main shoe, and means for directly applying the main shoe to the drum in addition to its application through the connection with the 30 servo shoe, substantially as set forth.

3. In a brake for a vehicle, the combination of a drum, a main segmental shoe inside said drum, a servo segmental shoe inside 35 said drum and on the opposite side of the axis thereof from said main shoe, a fixed pivot for one end of said main shoe, an operative connection between the other end of said main shoe and the adjacent end of said servo shoe, including a lever and a cam

operated thereby, said cam engaging said 40 main shoe, and a link from the lever to the servo shoe, substantially as set forth.

4. In a brake for a vehicle, the combination of a drum, a main segmental shoe inside said drum, a servo segmental shoe also 45 inside said drum and on the opposite side of the axis of said drum, a fixed pivot in one end of said main shoe, an operative connection between the other end of said main shoe and the adjacent end of said servo shoe, 50 means for applying the servo shoe to the interior of said drum, said operative connection between the shoes comprising a pivoted cam engaging the main shoe, a lever on the cam, and a link from the lever to the servo 55 shoe, and means for actuating the cam directly as well as from the servo shoe, substantially as set forth.

5. In a brake for a vehicle, the combination of a drum, a main segmental shoe inside said drum, a servo segmental shoe also 60 inside said drum and on the opposite side of the axis of said drum, a fixed pivot in one end of said main shoe, an operative connection between the other end of said main shoe and the adjacent end of said servo shoe, 65 means for applying the servo shoe to the interior of said drum, means for directly applying the main shoe to the drum in addition to its application through the connection with the servo shoe, a radius rod G free to swing about the axis of the drum, said servo shoe being pivoted to said radius rod, 70 substantially as set forth.

In testimony whereof I have signed my 75 name to this specification.

LOUIS COATALEN.
